UNITED STATES PATENT OFFICE.

JOSEPH LEDWINKA, OF PHILADELPHIA, PENNSYLVANIA, ASSIGNEE TO EDWARD G. BUDD MANUFACTURING CO., OF PHILADELPHIA, PENNSYLVANIA, A CORPORATION OF PENNSYLVANIA.

LATCH MECHANISM.

Application filed January 29, 1925. Serial No. 5,423.

My invention relates to latch mechanisms of the type applying particularly to the doors of closed body vehicles, especially automobiles. Whether the body is of the permanently closed type,—as, for example, the case of the sedan or the coupé,—or is, on the other hand, of the temporarily closed type,—as the roadster or coupé provided with a winter enclosure,—is immaterial, as 10 my invention applies to both alike. Too, while of major application in this field, some minor application may be found in other fields more or less related to this one.

The primary object of locks of this type 15 is the embodiment of the construction which admits of the employment of a door window-pane of substantially the full width of the door and the consequent reduction of the opaque projection of the vertically extending door rails to a minimum, thereby 20 widening substantially the range of window vision of the occupants of the car. There are thereby obtained not only greater pleasure and comfort for the occupants, but also 25 a markedly increased safety, since every obstruction to vision is a menace. Full or perfect vision is the ultimate aim, but this of course is impossible of attainment by reason of the practical necessity of some form of 30 support for the top of the car. But by means of this invention, as by means of others in the same field, a construction which most closely approaches this full and perfect vision may be secured.

Particularly, my present invention is an 35 improvement over and above that form of such latch mechanisms covered by the U. S. Patent to Kleinsmith, No. 1,348,882, granted August 10, 1920. The form of latch mechanism originated by Kleinsmith comprises 40 two latch-operating devices adapted to be located respectively on the outside and on the inside of the door, and to encompass between them a substantially free space 45 through which the window pane may be operated without interference from the latch-operating devices, and an interlocking member which circumvents this free space and the edge of the window pane in any of its 50 positions from uppermost to lowermost position, this interlocking member being of U-form. A U-shaped frame is pivoted below the edge of the window glass in its lowermost position and has branches extending

upwardly on opposite sides thereof to the 55 respective latch-operating devices. The frame oscillates.

One of the aims of my invention is to adapt this form of lock for more ready application to doors having transversely curved 60 walls which, by reason of the rectilinear movement of the window glass, very materially narrows the available space for the interlocking member. I aim, further, to have my latch mechanism, and particularly 65 the interlocking means, occupy a minimum space, a space compatible with the available space so restricted by the curved form of the door panels. Still further, I aim to combine such a latch-operating member with 70 those practical latch-operating devices, such as roll-backs, levers and spindles, which are necessary for reliable, efficient and satisfying service. And, finally, I aim to embody 75 in the latch mechanism at large those features of independent operation from inside and outside having to do with the same efficient and satisfying service.

There are yet other aims which I have 80 realized which will appear as understanding of the invention progresses. Prominent among them are the general simplification of the combination and its elements, the elimination as far as possible of parts which 85 may rattle, and the construction of those remaining parts and their bearings so that liability to loosen and introduce lost motion and rattle is reduced to a minimum.

The aims of my invention I reach in the main by circumventing the free space for 90 the window glass by means of an interlocking member which is bodily reciprocated rather than oscillated or rocked, or subjected to a movement of linear progression. One branch of the interlocking member I 95 operate under tension and the other under compression only, whereby I am enabled to maintain the section of the branch under tension of a form compatible with the available restricted space, even an extremely narrow space imposed by extreme curvature of the door panel. The remaining advantages 100 follow from this construction in combination with the devices now to be described.

Of the drawings:

Fig. 1 is a side elevation of the sedan body, two adjoining doors of which are shown to be equipped with my invention.

Fig. 2 is a substantially central transverse section through the inside and outside latch-operating devices of each door.

Fig. 3 is a sectional elevation of the inside latch-operating device taken on line 3—3 of Fig. 2.

Fig. 4 is a similar elevation of the outside latch-operating device taken on the line of that number in Fig. 2.

Fig. 5 is a general side elevation of the entire latch mechanism, including the interlocking member as it would appear if removed from the door, or before attachment to the door, with the parts arranged in the relation which they are intended to occupy in the door.

Fig. 6 is a corresponding front end elevation.

Fig. 7 is a cross-sectional detail of a portion of one branch of the interlock taken on line 7—7 of Fig. 5.

Fig. 8 is a front elevation of a modified form of inside latch operating device, corresponding in the main to that shown in Fig. 3, and

Fig. 9 is a transverse section of this modification on line 9 of Fig. 8.

The front and rear doors of the body are designated respectively 10 and 11. In this body they close toward each other. Each is provided with one of the latch mechanisms of my invention shown in side and end elevation in Figs. 5 and 6. In this embodiment these latch mechanisms are independent, in that the bolts 12 engage independent keepers 13 mounted on opposite faces of the intermediate B—C post (see Fig. 2). But I wish it to be understood at the outset that my invention may be practiced with dependent as well as independent latch mechanisms in adjacent doors. Moreover, that it is independent of the form of bolt employed, whether that type be of the sliding bolt herein described, or whether of the swinging latch bolt, and whether these latch bolts be mounted upon the door or upon the door post, and whether they are used singly or in multiple.

Numerical 14 is the inside latch-operating mechanism and 15 is the outside latch-operating mechanism (Figs. 5 and 6) while 16 is the interlocking member.

The latch operating device 14 (see Figs. 2 and 3) comprises a base plate 18 having a frontal flange 19, a slideable bolt operating member 20 on the head of which is mounted the sliding bolt 12, an overlying slide plate 21 therefor, a stamping of channel section having lip flanges 22 by means of which it is secured to the base plate, a primary bolt operating member 23 in the form of a bell crank pivoted at 24 to the base plate 18, and having a vertical arm or lever 25 engaging pin 26 in the slideable bolt operating member 20 within the flaring hook 27 of

its upper end, and the secondary operating member 28 in the form of a vertically extending lever carried in the plane of the lever arm 25 from the same pivot at 24 as the bell crank 23, (the lower end being offset for this purpose,) and provided at its upper end with an operating handle 29. The bolt may be operated to retract it by handle 29 by moving it to the left, as viewed in Fig. 3, the edge of lever 28 bearing against the contiguous edge of lever 25 of the bell crank. It is projected forwardly by the spiral spring 30 housed within the elongated slot 31 in its main body and bearing at its opposite ends against the fore end 32 of the body and a lug 33 struck inwardly from the base plate 18 and projecting transversely of the slot 31. The end of the bolt 20 coating with the primary and secondary operating members 25 and 28 is cut away for a depth sufficient to accommodate the thickness of members 25 and 28, and the height of pin 26 (see Fig. 2) and the depth of the channel sectioned guide 21 is maintained substantially uniform excepting for an increase of depth at its fore end 34, designed the better to accommodate and guide a spiral spring of proper proportions.

This inside latch operating device 14 is adapted, by reason of the form of its base plate 18 and its general structural configuration, to be located at the inside of the door, as shown in Fig. 2. The body of its base plate 18 is rested at its front margin upon the inturned flange 35 of the Z-sectioned door rail 36, its flange 19 is founded against the inner arm 57^a of the rail 36, and its rear margin bears against the inner lock board 37 by means of the projection 38, or a multiple number of such projections which are die-pressed from the body of the base plate. Securement is by any well known means, and is not shown.

The outside latch-operating device 15, shown particularly in Figs. 2 and 4, comprises a base plate 39 having a frontal flange 40; a slideable bolt operating member 41 arranged to slide, not transversely like the bolt operating member 20 of the inside latch operating device, but substantially vertically of the base plate; a guiding member 42 therefor like the guiding member 21, of channel section having lip flanges 43 by means of which it is secured to the base plate, and a secondary latch-operating member in the form of a double winged roll-back 44, engaging roll-back followers or talons 45 connected with the follower 41, which roll-back is operable through the usual transverse spindle 46, to which is applied the operating handle 47 on the exterior of the door. By rotating handle 47 in either direction, the slideable bolt operating member 41 is retracted upwardly in a substantially vertical direction. It is normally projected forwardly

by a spiral spring 48 carried by a stud 49 secured upon semi-circular extension 51 of the base 39. This spring 48 bears against its upper or rear end. The slideable bolt operating member 41 itself is a pressed metal stamping, as are substantially all the principal members of the latch mechanism. It is provided with side flanges 52, spacing its main body above the base plate substantially to the depth of the guide channel 42 and therefor serving as guides, is provided further with a depending rear flange 53 of slightly less height than the flanges 52, whereby undue friction with the base plate is avoided and against this rear flange the end 54 of projecting spring 48 bears. The body of the stamping 41 is entirely cut away surrounding the roll-back 44, and the roll-back followers or talons 45 are formed of this struck-away portion. Like the rear flange 53, they too are of lesser depth than the side flanges 52, and for the same purpose. The lower end of the stamping 41, designated 55, is extended forwardly of the base plate and is tapering in outline.

This latch-operating device of Figs. 2 and 4 is adapted to be mounted toward the outside of the bolt. The frontal margin of the base plate 39 is adapted to rest against and be founded upon the front face of the glass run channel 56, while its frontal flange 40 is founded upon and secured to the branch 57 of the door rail 36 by any chosen means. A latch locking device 58 indicated in general in Fig. 2 (and not a part of the present invention) projects through the web of door rail 36 and may be operated from the edge of the door when the door is open. A bridge 59 across the guide 42, having a top 60 bearing against the outer panel 61, serves for the mounting of the escutcheon 62 usually provided to finish the outside appearance.

The interlocking member 16 of the latch mechanism (Figs. 1, 5 and 6) is in the form of a U-shaped frame of rigid and semi-rigid construction. The inner branch 63 is of rigid construction, being of the thickened section shown in Fig. 7, and is provided with a central stiffening bead 64. It may be given any other section adapting it to resist bending moments when placed under compression. At its upper end it is connected by the pin and slot connection 65-66, which provides lost motion, with the arm 67 of the bell crank 23. Its lower end is offset outwardly as at 68 and then extended downwardly to meet the oppositely shaped lower end of the outer branch 69, which is secured thereto. Together, these lower ends of branches 63 and 69 are passed through a slotted guide 70 borne by a bracket 71 adapted to be attached to the web of door rail 36. Mounted within the slotted guide 70 and exerting sufficient pressure between the guide and the inter-

locking member to keep out lost motion and rattle, is the anti-rattle spring 72, which in the embodiment shown is secured to the interlocking member by the same means 74 by which the branches thereof are secured together. The outer branch 69 is of a thin and flat section, as may be discerned from Figs. 5 and 6, and of a semi-rigid nature, being in the form of a flexible strap of comparatively thin cross section. Nevertheless, the offset 68 of its lower end is of sufficient stiffness to render the entire right portion of the interlocking member 16 substantially rigid. At its upper end it is connected pivotally by means of the pin 75 with the depending lower end 55 of the slideable bolt operating member 41 of the outer latch-operating device 15. And I have offset the inner and outer branches 63 and 69 of interlocking member 16 to lie in different transverse planes, as clearly appears in Figs. 1, 5 and 6, whereby the outside latch-operating device 15 may occupy a position toward the lock rail 36 of the door in advance of the inside latch-operating device 14, and whereby differences in location of the secondary latch-operating members comprising the lever 28 and the roll-back 44 may be compensated for.

So organized, my invention achieves all of the objects which I set out to attain. The outside latch-operating device 15 is nested right up against the glass run 56 itself, as close as it is possible to get to the window glass 76. The glass run itself is located close up against the rabbet 77 in the door rail 36. So, the outside branch 69 of the interlocking member 16 projects substantially vertically downward to the restricted space through which it must pass between the outer door panel 61 and the bottom edge of the glass 76 in its lowermost position, insuring a direct and unbiased pull upon the interlocking member. In opening the door from the outside, the handle 47 may be operated in either direction, and in either case the slideable bolt operating member 41 is lifted, pulling (not pushing) upon the thin, flexible branch 69 of the interlocking member and thereby lifting said member bodily through its guide 70, and through compression of the inside branch 63, operating the bell crank 23 to reciprocate transversely the slideable bolt operating member 20 of the inside latch-operating device 14. This is accomplished without lost motion by reason of the fact that end 65 normally rests in the bottom of slot 66 at the upper end of the branch 63 of the interlock. Upon release of operating handle 47, spring 48, in conjunction with spiral spring 30, returns the parts to their normal positions. Spring 30, acting through branch 63, precludes the application of a compression force to the branch 69, and precludes its buckling. This operation is en-

tirely independent of the inside latch-operating member 28, and this latch-operating member is not moved from its normal position, since the cut-away portion of the sliding member 20 is of such extent that the sliding member does not engage the lever in its reciprocation.

To operate the latch mechanism from the inside, handle 29 is grasped and lever 28 pulled back, whereupon the bolt operating member 20 is, in this case, drawn back by direct engagement of levers 28 and 25. In this case neither the outside operating mechanism 15 nor the interlocking member 16 is moved, since end 65 moves upwardly of slot 66 and the lost motion precludes any moving engagement with the parts. So, operation by the inside device 14 is in turn, while still through the common primary operating member 23, likewise independent of the operation of the outside device 15. And by reason of the fact that the outside operating device and the interlocking member 16 remain at rest in this operation, projecting spring 30 needs be of moderate strength only. Both the inside and the outside latch-operating devices are of essentially simple construction, formed for the most part of the simplest sheet metal stampings, secured together by the simplest and most sturdy and durable means, configured and connected together so that there is an utter absence of that lost motion which may inhibit rattle. Yet the interconnection through the interlocking member 63 is positive, direct and effective. The free space for the window glass encompassed by the devices 14 and 15 is circumvented entirely by the interlocking member 16, and the form of this member is such that it may be most readily adapted to meet any degree of extreme movement of the window glass without interference, and be accommodated in the narrowest of available spaces. Indeed, the form of the outer tension branch 69 is such that even if it should rub upon either the lower edge of the glass or the outer panel of the door, there would be such inconsequential friction, and such slight deflection of this inflexible member as might follow would not impair the excellent operation in any way. Making the spiral spring 30 sufficiently strong not only to project bolt 12, but also to return the interlocking member 16, keeps the entire train of operating devices from the bolt 12 all the way through to the roll-back 15 under the tension of the spring, and effectively precludes longitudinal rattle thereof.

The modification of Figs. 8 and 9 does not differ materially from the inside locking device of Figs. 2 and 4 except in the substitution of the vertical rotatable spindle 77 for the vertical oscillatable operating lever 28. This spindle directly engages the slideable bolt operating member 20 through cam

arm 78 on its lower end, which engages the follower projection 79 projected upwardly from the upper side of the sliding member 20. This spindle is operated by the usual handle 80. The upper end of the long branch 63 of interlock 16 is provided with an anti-rattling spring 81 secured at the lower end to the main body of this branch, and having its bowed upper end projecting between the branch 63 and the arm 78 of the bell crank lever 23, the parts being confined by the shouldered machine screw 65 with clearance for the spring. So rattle is prevented. (The same construction is shown in the form of Fig. 3.) Otherwise the organization of this modification of the inside latch-operating device 14 is essentially similar to the form first described and the parts are accordingly similarly numbered.

There are without doubt yet other modifications of my invention which embody its generic spirit. All such modifications of the whole or any of its parts I aim to comprehend in the annexed claims.

What I claim is:

1. A door latch mechanism comprising inside and outside latch-operating devices adapted to be mounted on opposite sides of the door with free space between them, and a reciprocable interlock between said operating devices which circumvents the free space between the operating devices, said interlock comprising two circumventing branches, one on each side of the plane of said free space, one of which is operated always in tension and the other of which is operated always in compression.

2. A door-latch mechanism comprising inside and outside latch-operating devices adapted to be mounted on opposite sides of the door with free space between them, and a reciprocable interlock between said operating devices which circumvents the free space between the operating devices, said interlock comprising two circumventing branches, one on each side of the plane of said free space, the outside branch of which is operated always in tension and the inside branch of which is operated always in compression.

3. A door latch mechanism comprising inside and outside latch-operating devices adapted to be mounted on opposite sides of the door with free space between them, and a reciprocable interlock between said operating devices which circumvents the free space between the operating devices, said interlock comprising two circumventing branches, one on each side the plane of said free space, the outside branch of which is flexible and the inside branch of which is stiff and inflexible.

4. A door latch mechanism comprising inside and outside latch-operating devices adapted to be mounted on opposite sides of

- the door with free space between them, and a reciprocable interlock between said operating devices which circumvents the free space between the operating devices, together with a relatively fixed guide for that portion of said interlock most distantly removed from said free space.
5. A door latch mechanism comprising inside and outside latch-operating devices adapted to be mounted on opposite sides of the door with free space between them, and a reciprocable interlock between said operating devices which circumvents the free space between the operating devices, together with a relatively fixed guide for that portion of said interlock most distantly removed from said free space, which guide is adapted to be attached to the lock-rail of the door.
10. 6. A door latch mechanism comprising inside and outside latch-operating devices adapted to be mounted on opposite sides of the door with free space between them, and a reciprocable interlock between said operating devices which circumvents the free space between the operating devices, together with a relatively fixed guide for that portion of said interlock most distantly removed from said free space, and an anti-rattling device associated with said interlock and guide.
15. 7. A door latch mechanism comprising a member slidable in the plane of the door, a primary operating lever for said slidable member, a secondary operating lever adapted to move the slidable member through the intermediary of said primary operating member only, a second secondary operating member separated from the first by a free space, and a link connection between said second secondary operating member and the primary operating member, embodying a lost motion connection and circumventing said free space.
20. 8. A door latch mechanism comprising inside and outside latch operating devices adapted to be mounted on opposite sides of the door and to embrace a sliding window therebetween, and a reciprocable interlock circumventing said sliding window whereby to interlock said operating devices.
25. 9. A door latch mechanism comprising inside and outside latch operating devices adapted to be mounted on opposite sides of the door and to embrace a sliding window therebetween, and a reciprocable interlock interconnecting said operating devices, said interlock being disposed in the general plane of the body of the door and arranged for circumvention of said sliding window.
30. 10. A door latch mechanism comprising inside and outside latch operating devices adapted to be mounted on opposite sides of the door whereby to accommodate therebe-
- tween a sliding window of a width substantially equal to the full width of the door, and a vertically reciprocable interlocking device interconnecting said operating devices whereby to provide for actuation of said latch by either of said operating devices.
35. 11. A door latch mechanism comprising inside and outside latch operating devices adapted to be mounted on opposite sides of the door whereby to accommodate therebetween a sliding window of a width substantially equal to the full width of the door, and an interlocking device interconnecting said latch operating devices, said interlocking device circumventing one edge of said sliding window, and being bodily reciprocable by actuation of one of said latch operating devices.
40. 12. A door latch mechanism comprising inside and outside latch operating devices adapted to be mounted on the door in such manner as to accommodate therebetween a sliding window of a width substantially equal to the full width of the door, said latch-operating devices each embodying an element movable in different planes, respectively, to actuate the latch, and an interlocking member between said operating devices embracing the path of movement of said sliding window and adapted to be vertically lifted by one of said operating devices to actuate the latch.
45. 13. A door latch mechanism comprising inside and outside latch operating devices adapted to be mounted on the door in such manner as to accommodate therebetween a sliding window of a width substantially equal to the full width of the door, said operating devices each embodying an element operable by different movements, respectively, to actuate the latch, an interlocking member interconnecting said operating devices and embracing the path of movement of said sliding window, said interlocking member being bodily liftable by one of said operating devices, and means between said interlocking member and the other of said operating devices for coordinating the different movements of said operating devices.
50. 14. A door latch mechanism comprising a bolt adapted to be located on one side of the door, inside and outside operating devices for actuating said bolt, one of said operating devices being spaced from said bolt and the other operating device in order to accommodate a sliding window therebetween, and means interconnecting said devices and circumventing the bottom edge of said sliding window and bodily reciprocable by operation of one of said operating devices to actuate the other of said devices.
55. 15. A door latch mechanism including a bolt adapted to be located on one side of the door, inside and outside operating devices for said bolt arranged on opposite sides of

- the door to accommodate a sliding window therebetween of a width substantially equal to the full width of the body of the door, and a bodily vertically liftable member circumventing one edge of said sliding window and interlocking said bolt operating devices, one of said connections between said operating devices and said interlocking member embodying a lost motion.
16. The combination with a door adapted to have a sliding window of a width substantially equal to the full width of the body of the door, of a latch mechanism therefor including a bolt, inside and outside operating mechanisms for said bolt located on opposite sides of the path of movement of said sliding window, said mechanisms including elements rectilinearly and oscillatably shiftable, respectively, and an interlocking member interconnecting said elements whereby one may be operated by the other to actuate said bolt.

In testimony whereof I hereunto affix my signature.

JOSEPH LEDWINKA.
